UNITED STATES PATENT OFFICE

2,175,835

HOLDING DEVICE FOR CORD, WIRE, ETC.

Roger Fraser, Brooklyn, N. Y.

Application November 4, 1938, Serial No. 238,789

2 Claims. (Cl. 242—135)

My invention relates to supports and refers more particularly to a device for supporting cord and wire, etc., and a severing means therefore and contemplates new and useful improvements thereupon.

One object of my invention is to provide a cord holding device with a tubular cord holder rotatably and frictionally engageable with spring lugs.

10 Another object of my invention is to provide a cord holding and cutting device with means for rotatably and frictionally holding a cord holding device.

15 A further object of my invention is to provide a wire holding device utilizing wire holding spools with a central bore and rotatably and frictionally holding the spools by means of spring lugs with portions upset into the central bore of the spools.

20 A still further object of my invention is to provide a wire holding device, wherein the wire is wound on spools provided with extended, shouldered ends that rotatably and frictionally engage with openings in spring lugs, to provide a manually operable wire cutting means integral 20 with the device and means for detachably holding the device positioned as desired in any suitable place.

25 I attain these results preferably by the means illustrated in the accompanying drawing, wherein like numerals refer to similar parts throughout the several views, in which:

Figure 1 is a side elevation of the device illustrating the relative positions of the tube holding the cord.

30 Figure 2 is a plan of Figure 1 illustrating in further details, the spring clip and one of the supporting means.

35 Figure 3 is a plan of a wire holding device, illustrating the detachable means for holding the device positioned, the spring clip positioned over the shouldered ends of the wire spool and the wire cutting means.

Figure 4 is a side elevation of Figure 3.

40 Figure 5 is an enlarged section, taken on lines 5—5, of Figure 2.

Figure 6 is an enlarged section, taken on lines 6—6, of Figure 3.

45 Figure 7 is an enlarged end elevation of Figure 2, taken on lines 7—7, of Figure 2.

50 Figure 8 is an enlarged elevation of Figure 3, taken on lines 8—8, of Figure 3.

55 Figure 9 is a partial enlargement, partly in section, illustrating one of the means for rotatably holding the wire spool.

Figure 10 is a partial plan of a modification of the hole 20 shown in Figure 2.

In Figures 1, 2, 5, and 7, the base or plate 1 is provided with four spring lugs 2, 3, 4, and 5, each having openings like 6, 7, see Figure 1, which engage with the tubular portions 8, 9 that carry cord 10, 11 in frictional engagement with the spring lugs.

The plate 1, is also provided with an upstanding portion 12, see Figures 1, 2 and 7, which carries 10 integral with it a cutting means 13.

The plate 1 is suitably formed at the upper end 14 with a bayonet slot 15 having a large portion 16 to pass the head of a screw or nail and a smaller portion 17 that is smaller than the 15 nail or screw head, not shown.

The opposite or bottom end 18 has a portion 19 provided with a hole 20 for a nail or screw, and it is obvious that this hole 20 could be like 15 if desired, so that when using the holes 15 and 20 20 the device would be fixed to an object or place and if both holes were like 15 the device would be detachable from the nails or screws and it is noted that this portion 19 is upset from the plate 12, as shown by 21 in Figures 7 and 8. 25

Figures 3, 4, 6 and 8 illustrate a modification of the device shown in Figures 1, 2, 5 and 7 wherein the base 1 has the holes 15 on both ends, showing the device detachable and the wire spools 22 and 23 that are provided with shouldered extensions 24 and 25 that rotatably and frictionally engage with the openings 26, 27, 28 and 29. 30

The upstanding end 30 of Figures 3, 4 and 8 is modified to provide a cutting edge 31, for the wire, that engages with the manually operable 35 knife 32, pivoted at 33.

Figure 9 is a modification of Figure 3 wherein the spring lug 4 is upset inwardly at 34 to provide a portion frictionally engaging within the bore 35 of the spool to hold the spool for retarded rotation. 40

In Figure 10 the hole indicated by numeral 20 in Figure 2 is made into a slot 35 which may be utilized in either of the devices shown in Figures 2 and 3. 45

These supports as illustrated and described are simple in construction and efficient in operation, providing a quick and easy means of attachment to places desired.

Having thus illustrated and described the preferred embodiment of my invention, I do not wish to limit myself to the exact construction or arrangement of parts shown, since it is self evident that modifications may be made therein, without 50 55

departing from the spirit of the invention or scope of the claims.

I claim:

- 5 1. A cord holding device comprised of a plate, a plurality of upwardly turned spring lugs on the sides thereof, a tubular means carrying a ball of cord intermediate its ends, openings in said lugs in which the ends of said tubular means are engaged, one end of said plate provided with an upwardly turned portion having a cord cutting means integral therewith and extensions integral with said plate, on opposite ends thereof, providing means holding the device in any suitable position.
- 10

2. A cord holding device comprised of a plate, a plurality of upwardly turned, oppositely arranged spring lugs on the sides thereof, a tubular means carrying a ball of cord intermediate its ends, openings in said lugs in which the ends of said tubular means are rotatably engaged, one end of said plate provided with an upwardly turned portion having a cord cutting means integral therewith and extensions integral with said plate, on opposite ends thereof, providing means holding the device in any suitable position. 5

ROGER FRASER.
